UNITED STATES PATENT OFFICE.

LOUIS DESTRÉE, OF HAREN, BELGIUM.

SKEIN-CLIP.

No 801,064.

Specification of Letters Patent.

Patented Oct. 3, 1905.

Application filed August 27, 1904. Serial No. 222,393.

To all whom it may concern:

Be it known that I, LOUIS DESTRÉE, manufacturer, a subject of the King of Belgium, residing at Haren, Belgium, have invented new and useful Improvements in or Relating to the Dyeing of Hanks of Yarns; and I do hereby declare the following to be a full, clear, and exact description of the same.

This invention relates to an improved apparatus and devices for forming skeins of yarn into continuous bands capable of being treated by the same processes and on the same apparatus as those used in dyeing fabrics, so that the skeins instead of each requiring a series of accessory operations as hitherto effected by skilled handwork are dyed in the same way as fabrics in a continuous and economical manner.

The various operations for forming skeins into continuous bands are illustrated, by way of example, in the accompanying drawings, which also show a few examples of clips used in forming bands of skeins.

Figure 1 shows a mechanical device enabling bands of skeins to be formed in a continuous manner before they are introduced into the dye-bath. Fig. 2 is a perspective view of a stick serving to receive the halves of the clips during the formation of the band of skeins. Figs. 3 and 4 show diagrammatically two methods of carrying out the operation of forming the bands. Fig. 5 is a detail view of the double hooks of the device shown in Fig. 1. Figs. 6, 7, 8, and 9 are various constructions of clips. Figs. 10 and 11 show a skein on a clip. Fig. 12 shows a band of skeins.

The formation of the said bands is effected in the following manner and by means of the device shown in Fig. 1: This device comprises two rollers 1, 2, capable of turning in bearings 3, secured to the wall or support, preferably above the dyeing-bath. The upper roller 1 is provided with a crank 4. Over these two rollers pass endless belts 5, 6, provided with double hooks 7, Fig. 5, or their equivalents, secured to the belts at suitable intervals for receiving the ends of the hollow-channel form-stick 8, of semicircular cross-section, on which can be placed any number of skeins to be dyed after the two halves of one of the clips (shown, by way of example, in Figs. 6 to 9) have been placed into the groove of the stick. (See Fig. 3.) The stick, with the skeins, being suspended on the hooks of the belts 5 and 6, one of the halves of the clip is lowered along the threads of the skeins until that half

is at the bottom end of the skeins arranged on the stick 8. This series of skeins is then lowered to a suitable extent by turning the crank 4 or otherwise until it occupies the position *a*, Fig. 1, and a second stick 8, also containing two clip-halves and carrying a series of skeins, is suspended from the hooks 7 above the skeins *a*, as shown at *b*, Fig. 1. One half-clip of the upper stick is then lowered along the upper skeins *b* (as previously for *a*) until it arrives at the lower end of the series *b*, where the two clip-halves are joined, one of the series *a* and the other of the series *b*, Figs. 3 and 4. The rollers 1 and 2 are again operated by the crank 4 to lower the series *a* and *b*, and a new series is suspended to the hooks and connected up in the same way. After each connection of two series of skeins the stick 8 is withdrawn, as it is merely used for temporarily suspending the skeins.

The different series of skeins can be connected to each other by any suitable flat form of clip. Fig. 6 shows a clip the two halves of which are formed by flat bars or bands 9 and 10, provided on their inner edges with projections 11, serving to prevent the skeins from sliding laterally. The band 9 is provided at the two ends with two hooks 12, capable of engaging two eyes 13 in the other band 10, as well as a hook 14, arranged in the center of the band 9 and capable of engaging with an eye 15 on the band 10. Fig. 7 shows a similar clip, except that the projections 11 are replaced by recesses 16. In the clip shown in Fig. 8 the two bands 9 and 10 are provided with opposite inwardly-directed fingers 17, provided with corresponding holes, through which passes an iron wire 18, which forms the connection.

Fig. 9 shows another construction of a clip before and after the connection of the two halves.

The band or chain of skeins having been formed in the manner described, it can be drawn through the dyeing-bath as it is being formed, or the band can be rolled up on a roller 19, Fig. 12, whence it will be subsequently unwound for dyeing, as is generally done with fabrics.

This method of dyeing yarns previously formed into bands of any desired length and width enables the work to be carried on very quickly, cheaply, and hygienically and to be carried out by ordinary workmen and requires less labor than dyeing according to the method hitherto employed.

Having fully described my invention, what I desire to secure by Letters Patent is—

In a clip for forming series of hanks of yarn into a continuous band, the combination with 5 a flat flexible metal bar, a longitudinal eye at the upper edge of each end of said bar, a projecting eye at the central part of the same, and a plurality of suitable projections on the upper edge of the bar, the distance between 10 said projections corresponding to the width of a hank of yarn, of a second flat flexible bar, a downwardly-extending hook at each end of said second bar and adapted to be engaged into the longitudinal eyes of the first-

named bar, a forwardly-extending hook at 15 the central part of the second bar and adapted to engage the central eye of the first-named bar, and a plurality of projections on the lower edge of the second bar and registering with the projections of the first-named bar, 20 substantially as set forth.

In testimony whereof I have signed this specification in the presence of two subscribing witnesses.

LOUIS DESTRÉE.
